UNITED STATES PATENT OFFICE.

FRANCIS J. LYONS, OF ST. LOUIS, MISSOURI.

RETAINING DEVICE FOR STORM-SLIPPERS, &c.

SPECIFICATION forming part of Letters Patent No. 607,061, dated July 12, 1898.

Application filed April 7, 1897. Serial No. 631,194. (No model.)

To all whom it may concern:

Be it known that I, FRANCIS J. LYONS, a citizen of the United States, residing at the city of St. Louis, State of Missouri, have invented a certain new and useful Improvement in Retaining Devices for Storm-Slippers, &c., of which the following is a full, clear, and exact description, reference being had to the accompanying drawings, forming

10 a part of this specification, in which—

Figure 1 is a view illustrating my improved retaining device in position on the wearer's foot. Fig. 2 is a plan view of the device detached. Fig. 3 is a similar view showing the 15 clamping-jaws open. Fig. 4 is a detailed view of the hinged end of one of the clamping-jaws. Fig. 5 is a detailed view of the operating-lever for the clamping-jaws, and Fig. 6 is a detailed view of the link.

20 This invention relates to a new and useful improvement in retaining devices for storm-slippers and the like, the object being to provide a device of the character described which can be adapted to or used in connection with ordinary storm-slippers, the device 25 coöperating with the foot of the wearer to clamp the storm-slipper in position, so that it cannot be pulled off in ordinary wear, such as is frequently experienced in the wearing of 30 ordinary "overshoes" or "rubbers," as they are sometimes called, such overshoes remaining in the mud or mire instead of being retained on the wearer's foot when the foot is lifted.

35 With this object in view the invention consists in the combination, with a storm-slipper, of a device attached thereto and adapted to coöperate with the wearer's foot to retain said storm-slipper in position on the wearer's foot.

40 Another object of the invention resides in the novel construction of this retaining device, which consists of two pivoted embracing jaws with means for coöperating with each of said jaws for opening and closing 45 said jaws.

Other features of invention reside in the construction, arrangement, and combination of the several parts, all as will hereinafter be described and afterward pointed out in the 50 claims.

In the drawings, A indicates an ordinary

storm-slipper or overshoe to which is applied my improved retaining device.

B and B' indicate two embracing jaws pivoted together, said jaws being provided with 55 bearings b and b' near their pivoted ends. In the bearings b is pivoted an operating-lever C, which operating-lever carries a pivot-stud c'. D indicates a link pivoted to the stud c' and the bearings b'. If desired to attach 60 these embracing jaws to the rear upper edge of a storm-slipper, I provide perforated extensions E on the jaws, as shown in Fig. 1, the jaws being secured to the storm-slipper by riveting, sewing, or otherwise. When it 65 is desired to put on a storm-slipper provided with my improved device, the lever is thrown open, as shown in Fig. 3, which permits easy manipulation of the slipper. When the slipper is in position on the wearer's foot, the lever C is turned in, as shown in Fig. 2, which, with the link D, forms a toggle-joint, locking 70 the jaws in place. The pivoted stud c' is mounted in a suitable offset in the lever C, so as to throw the pivotal connection of link 75 D, with the lever C, beyond dead-center when the lever is closed. The upper edge of the storm-slipper being usually of the height shown in Fig. 1 the jaws will grasp the small portion just above the heel, or more properly 80 the tendon of Achilles, and prevent the heel of the storm-slipper from becoming displaced in ordinary use. It is obvious that the jaws need not be permanently attached to the storm-slipper, but may be provided with biting 85 edges to coöperate with the storm-slipper, in which event the retaining device would be placed in position after the storm-slipper had been put on the wearer's foot.

I am aware that many minor changes in the 90 construction, arrangement, and combination of the several parts of my device can be made and substituted for those herein shown and described without in the least departing from the nature and principle of my invention.

While I have used the term "slippers," I desire it understood as including rubbers, overshoes, &c.

Having thus described my invention, what 100 I claim, and desire to secure by Letters Patent, is—

1. The combination with a slipper, of means for securing the same to the foot of the wearer comprising two embracing jaws pivotally united at their rear ends and each having provisions for direct attachment to the sides of the slipper, and means carried by the jaws and located at the rear thereof for expanding, compressing and locking the same, substantially as described.
- 5 2. The combination with a slipper, of means for securing the same to the foot of the wearer, comprising two embracing jaws pivotally united and each having provisions for direct

attachment to the sides of the slipper, and a toggle mechanism carried by the jaws and 15 spanning the pivotal connection, for locking, spreading and compressing the jaws, substantially as described.

In testimony whereof I hereunto affix my signature, in presence of two witnesses, this 20 20th day of March, 1897.

FRANCIS J. LYONS.
